CAR TRUCK

Rudolph Leppla, Davenport, Iowa, assignor, by
mesne assignments, to McConway & Torley
Corporation, Pittsburgh, Pa., a corporation of
Pennsylvania

Application April 10, 1941, Serial No. 387,938

4 Claims. (Cl. 165—190)

This invention relates to car trucks of the type in which both the transom and the bolster are supported upon cushioning springs, and more particularly to trucks in which the transom is movable downwardly into engagement with fixed seats on the side frames of the truck, and in which the transom is normally supported by its springs above the seat. A truck of the type referred to is shown in my U. S. Patent No. 2,317,891, granted April 27, 1943, on application Serial No. 386,702, filed April 3, 1941.

The present invention has for its object to provide an improved car body cushion comprising bolster and transom cushioning springs of different harmonic characteristics which by their combined action materially lessen the transmission of vibrations from the truck to the car body. A further object of the invention is to provide a transom cushion in the form of a single semi-elliptic spring which is centrally disposed with respect to the transom and which engages the bottom chord at points spaced a considerable distance from the center thereof, so that the stresses are advantageously distributed in the side frames.

With the above and other objects in view the invention may be said to comprise the car truck as illustrated in the accompanying drawing hereinafter described and particularly set forth in the appended claims, together with such variations and modifications thereof as would be apparent to one skilled in the art to which the invention pertains.

Reference should be had to the accompanying drawing forming a part of this specification, in which:

Figure 1 is a side elevation of the truck embodying the invention;

Fig. 2 is a fragmentary side elevation on an enlarged scale showing the central portion of the truck, portions of the side frame and transom being shown in section;

Fig. 3 is a section taken on the line indicated at 3—3 in Fig. 2; and

Fig. 4 is a section taken on the line indicated at 4—4 in Fig. 2.

Since the side frames of the truck and the supports for the opposite ends of the transom, spring planks, and bolster are identical, the accompanying drawing shows the construction at one side of the truck only, it being understood that this construction is duplicated at the opposite side of the truck, as is the usual practice in car truck construction.

Referring to the accompanying drawing, the

truck of the present invention has a bolster A upon which the car body is supported, a spring plank B which carries the cushioning springs upon which the ends of the bolster A rest, a transom C from which the spring plank is pivotally suspended, and side frames D in which the ends of the transom C are slidably mounted.

Each side frame D has an upper compression chord 1 and a lower tension chord 2 which connect journal boxes 3 located at opposite ends of the frame. The bottom chord 2 may be in the form of an upwardly facing channel and has a horizontal central portion 4 provided with deep side flanges 5. Adjacent opposite ends of the horizontal portion 4 of the bottom chord each side frame is provided with vertical guide columns 6 which connect the top and bottom chords and provide a substantially rectangular opening midway between the ends of the side frame in which an end of the transom C is guided for vertical movement. At their upper ends the columns 6 are provided with laterally offset portions 7 which widen the side frame opening immediately beneath the top chord 1.

25 The transom C has a pair of cross beams 8 which extend across the space between the side frames at right angles to the side frames and which are spaced apart a sufficient distance to receive the bolster A between them. The cross beams are rigidly connected at each end of the transom by a rectangular guide frame 9 which is slidable in the opening of the side frame between the guide columns 6. Each transom guide frame 9 has laterally projecting lugs 10 adjacent

30 the top thereof which overlie opposite sides of each of the guide columns 6. The height and width of the lugs 10 is such that when the guide frame 9 is elevated to a position adjacent the top chord 1, the lugs 10 may pass through the enlarged upper portion of the side frame opening. The bottom of the guide frame 9 has depending flanges 11 disposed centrally thereof and these flanges overlie the opposite sides of the bottom chord 2. The height of the flanges 11 is such

35 that when the transom guide frame 9 is elevated to its uppermost position in the side frame opening, the flanges 11 will be clear of the bottom chord so that the side frame may be readily removed. The lugs 10 and flanges 11 serve to guide

40 the frame 9 vertically and to hold the side frames against tilting or other angular movements with respect to the transom C. The spring plank B is suspended from the cross beams 8 by means of links 12 which are connected at their upper ends 45 to the cross beams by pivots 13 and at their low-

er ends to the spring plank B by pivots 14. The bolster A is supported at each end above the spring plank by means of suitable springs interposed between the spring plank and bolster, such as the nest of coil springs 15.

The transom is yieldably supported upon each side frame by means of a semi-elliptic spring 16 which is mounted in the deep horizontal channel of the bottom chord 2. The spring 16 has opposite end portions 17 which are slidably upon the bottom wall of the bottom chord adjacent the ends of the horizontal portion 4 and substantially beneath the vertical guide columns 6. The spring 16 is provided with a central band 18 which engages the bottom of the rectangular transom guide frame 9 centrally thereof. The spring 16 is held against longitudinal movements by means of lugs 19 on the bottom of the frame 9 which engage opposite ends of the band, and against lateral movements by a lug 20 on the band engaging in an aperture or recess in the bottom of the frame 9. The spring 16 normally projects above the side flanges 5 of the bottom chord and supports the transom above the bottom chord. The spring 16, however, is compressible into the channel of the bottom chord, and, when a predetermined downward pressure is exerted thereon, permits the frame 9 to seat upon the bottom chord.

The seat for the transom guide frame is provided by the upper edges of the side flanges 5 and cross webs 21 flush with the upper edges of the flanges and connecting the flanges adjacent the lower ends of columns 6. The capacity of the spring 16 may be such that when the car body supported by the trucks is empty or lightly loaded, the transom is supported above its seats and the car body is cushioned by both the bolster and transom springs. When the car is heavily loaded, the spring 16 is compressed by the load sufficiently to permit the transom to rest upon its seat and the cushioning of the car body is then effected by the bolster cushioning springs 15. The springs 15 may be designed to effectively cushion a heavily loaded car and the spring 16 to provide an effective cushion for an empty or lightly loaded car. In order for the bolster springs 15 to effectively cushion heavy loads, they must be very stiff, and for this reason they provide a poor cushion for an empty or lightly loaded car. The lighter spring 16, together with the springs 15, however, provide a soft cushion for a lightly loaded or empty car. The spring 16 also serves when the car is heavily loaded to cushion movements of the side frames with respect to the car body such as are due to passage of loose rail joints or to eccentric or flat wheels.

The combined action of the semi-elliptic springs 16 and the coil springs 15 is such as to materially lessen the vibrations transmitted to the car body when the transom is supported above its seat by the spring 16 by reason of the different harmonic characteristics of the coil and semi-elliptic springs. The spring 16 also serves to advantageously distribute the stresses imposed upon the side frames by reason of the fact that the load is transmitted to the side frames at points spaced a considerable distance from the center of the side frame and to points substantially beneath the vertical guide columns rigidly connecting the top and bottom chords of the side frame.

The spring supports of the present invention may also be used to advantage for cars which are not designed for carrying heavy loads, in which

case the car body is cushioned at all times by both the transom and bolster supporting springs, and the transom engages its seat only when excessive pressure is exerted upon the springs due to impact, in which case the transom cushioning springs serve to provide a softer cushion and reduce vibrations and have a snubbing action when the car or truck is subjected to heavy impacts.

It is to be understood that variations and modifications of the specific devices herein shown and described for purposes of illustration, may be made without departing from the spirit of the invention.

What I claim is:

1. In a car truck having side frames with top and bottom chords and columns spaced apart to provide central openings, the portion of the bottom chord of each side frame beneath the openings thereof being in the form of an open top channel, a transom having end portions guided for vertical movement in said openings, and having portions engaging said columns to hold the side frames against tilting movements with respect to the transom, a bolster yieldably supported by said transom, and a semi-elliptic transom supporting spring mounted in said channel having a central portion projecting above the bottom chord centrally of said opening, and end portions slidably engaging the bottom of the channel beneath said columns.

2. In a car truck having side frames with top and bottom chords and columns spaced apart to provide central openings, the portion of the bottom chord of each side frame beneath the openings thereof being in the form of an open top channel, a transom having end portions guided for vertical movement in said openings and having portions engaging said columns to hold the side frames against angular movements with respect to the transom, a bolster, supporting springs interposed between said transom and said bolster, said springs having a capacity and range of deflection sufficient to cushion maximum loads, and a semi-elliptic transom supporting spring mounted in said channel having a central portion projecting above the bottom chord centrally of said opening, and end portions slidably engaging the bottom of the channel adjacent said columns, said spring being compressible into said channel under a predetermined pressure greater than that imposed by a lightly loaded car but within the cushioning capacity of the bolster springs to permit the transom to seat upon said bottom chord.

3. In a car truck, a side frame having a top chord, a bottom chord in the form of a channel with upwardly extending side flanges and spaced columns connecting said chords and forming a central opening, said columns having webs extending across the bottom chord channel adjacent the top edges of the bottom chord flanges and terminating above the bottom of said channel, a transom having an end portion slidably in the side frame opening, a bolster yieldably mounted on the transom, and a semi-elliptic spring mounted in the bottom chord channel with its center arched upwardly and supporting the end portion of the transom above the bottom chord flanges and with its ends extending beneath the lower ends of the webs of the guide columns and slidably engaging the bottom of the bottom chord channel.

4. In a car truck, a side frame having a top chord, a bottom chord in the form of a channel

with upwardly extending side flanges, spaced columns connecting said chords and forming a central side frame opening and stop webs connecting the bottom chord flanges at their upper edges adjacent the columns, said webs being integral with the columns and bottom chord flanges, a transom having end portions guided between said columns and engageable with said

stop webs, and a semi-elliptic spring having end portions engaging the bottom of the bottom chord channel and a central portion extending above the bottom chord flanges to normally support the transom above and out of contact with said stop webs.

RUDOLPH LEPPA.
